(57) **ABSTRACT**

A stator blade including a blade body, a first insert, a second insert, and an end cover. The blade body has a first blade air passage and a second blade air passage extending in the blade height direction within the blade body. Each passage has an open end on a blade-height second side. The first insert and the second insert have tubular outer peripheral plate portions. A plurality of impinge holes are formed in the outer peripheral plate portion. The tube height opening side of the outer peripheral plate portion in the tube height direction is open. The outer peripheral plate portion of the first insert is disposed in the first blade air passage such that cooling air flows into the outer peripheral plate portion from

(Continued)

the opening of the first insert. The outer peripheral plate portion of the second insert is disposed in the second wing air passage.

**STATOR BLADE AND GAS TURBINE
COMPRISING SAME**

TECHNICAL FIELD

The present invention relates to a stator vane and a gas turbine including the same.

Priority is claimed on Japanese Patent Application No. 2021-053113, filed on Mar. 26, 2021, the content of which is incorporated herein by reference.

BACKGROUND ART

A gas turbine includes a compressor that compresses air to generate compressed air, a combustor that combusts a fuel in the compressed air to generate a fuel gas, and a turbine driven by the combustion gas. The turbine includes a turbine rotor that rotates around an axis, a turbine casing that covers the rotor, and a plurality of stator vane rows. The turbine rotor includes a rotor shaft around the axis, and a plurality of rotor blade rows attached to the rotor shaft. The plurality of rotor blade rows are aligned in an axial direction where the axis extends. Each of the rotor blade rows includes a plurality of rotor blades aligned in a circumferential direction with respect to the axis. The plurality of stator vane rows are aligned in the axial direction, and are attached to an inner peripheral side of the turbine casing. Each of the plurality of stator vane rows is disposed on an axial upstream side of any one rotor blade row of the plurality of rotor blade rows. Each of the stator vane rows includes a plurality of stator vanes aligned in the circumferential direction with respect to the axis.

The stator vane includes a blade body that forms a blade shape by extending in a radial direction with respect to the axis, an inner shroud provided on a radial inner side of the blade body, and an outer shroud provided on a radial outer side of the blade body. The blade body of the stator vane is disposed inside a combustion gas passage through which the combustion gas passes. The inner shroud defines a radial inner side edge of the combustion gas passage. The outer shroud defines a radial outer side edge of the combustion gas passage.

The stator vane of the gas turbine is exposed to a high-temperature combustion gas. Therefore, the stator vane is generally cooled by air or the like.

For example, a plurality of cooling air passages through which cooling air passes are formed in the blade body of the stator vane disclosed in PTL 1 below. Each of the plurality of cooling air passages extends in a blade-height direction Dh, which is the radial direction with respect to the axis. The stator vane includes an impingement plate disposed in one cooling air passage of a plurality of cooling air passages. The impingement plate is disposed inside one cooling air passage to extend inside the one cooling air passage in the blade-height direction Dh, and to partition the inside of the one cooling air passage into a blade surface side of the blade body and an inner side opposite to the blade surface side. A plurality of impingement holes are formed in the impingement plate.

In the stator vane, inside the one cooling passage, the cooling air flowing into the inner side with the impingement plate as a reference is ejected to the blade surface side from the plurality of impingement holes of the impingement plate. The cooling air ejected from the plurality of impingement holes collides with a portion having a back-to-back relation-

ship with the blade surface on a passage defining surface defining the one cooling air passage, and performs impingement cooling on the portion.

CITATION LIST

Patent Literature

[PTL 1] Japanese Patent No. 4885275

SUMMARY OF INVENTION

Technical Problem

15 With regard to the stator vane of the gas turbine, it is desirable to cool the stator vane and to reduce a usage amount of air for cooling the stator vane as much as possible while improving durability of the stator vane.

20 Therefore, an object of the present disclosure is to provide a stator vane capable of being efficiently cooled, and a gas turbine including the stator vane.

Solution to Problem

25 According to an aspect of the invention, in order to achieve the above-described object, there is provided a stator vane provided in a gas turbine.

30 The stator vane includes a blade body having a blade shape in a cross-section and extending in a blade-height direction having a direction component perpendicular to the cross section, a first insert and a second insert which have a tubular shape, extend in a tube-height direction, and are disposed inside the blade body so that the tube-height direction faces the blade-height direction, and an end cover.

35 The blade body includes a plurality of blade air passages extending in the blade-height direction inside the blade body. In the plurality of blade air passages, both a first blade air passage and a second blade air passage have an open end on a blade-height one side which is one side of a blade-height first side and a blade-height second side in the blade-height direction. Both the first insert and the second insert have an outer peripheral plate portion having a tubular shape and extending in the tube-height direction, and a sealing plate portion that closes an end on a tube-height sealing side which is one side of the outer peripheral plate portion in the tube-height direction out of two sides in the tube-height direction. The outer peripheral plate portion has a plurality of impingement holes penetrating from an inside to an outside of the tubular outer peripheral plate portion. A tube-height opening side which is the other side of the outer peripheral plate portion in the tube-height direction is open.

40 The outer peripheral plate portion of the first insert has a gap existing between the outer peripheral plate portion of the first insert and a first passage defining surface of the blade body defining the first blade air passage, and is disposed inside the first blade air passage so that cooling air flows into the outer peripheral plate portion from an opening of the first insert. The outer peripheral plate portion of the second insert is configured so that the tube-height opening side of the second insert faces the blade-height one side, has a gap existing between the outer peripheral plate portion of the second insert and a second passage defining surface of the blade body defining the second blade air passage, and is disposed inside the second blade air passage so that cooling air flows from an opening of the second insert. The end cover is provided on the blade-height one side of the blade body so that the cooling air ejected from the plurality of

45 50 55

60 65

impingement holes of the first insert to between the outer peripheral plate portion of the first insert and the first passage defining surface is guided into the second insert from the opening of the second insert through the opening of the first blade air passage, and covers the opening of the first blade air passage and the opening of the second insert.

In the present aspect, the cooling air flowing into the first insert disposed inside the first blade air passage performs impingement cooling on the first passage defining surface. Furthermore, at least a portion of the cooling air flows into the second insert disposed inside the second blade air passage. The cooling air flowing into the second insert performs impingement cooling on the second passage defining surface. Therefore, in the present aspect, the stator vane can be more efficiently cooled, and a usage amount of the cooling air can be reduced, compared to when cooling air A_C flowing into one insert is ejected to a combustion gas passage immediately after the cooling air A_C performs the impingement cooling on the inside of the blade body.

According to another aspect of the invention, in order to achieve the above-described object, there is provided a gas turbine.

The gas turbine includes a stator vane of the above-described aspect, a rotor that rotates around an axis, and a casing that covers an outer peripheral side of the rotor. The stator vane is fixed to an inner peripheral surface of the casing.

Advantageous Effects of Invention

According to an aspect of the present disclosure, a stator vane can be effectively cooled, and a usage amount of cooling air can be minimized while durability is improved.

BRIEF DESCRIPTION OF DRAWINGS

FIG. 1 is a schematic sectional view of a gas turbine according to an embodiment of the present disclosure.

FIG. 2 is a sectional view illustrating a main part of the gas turbine according to the embodiment of the present disclosure.

FIG. 3 is a perspective view of a stator vane according to a first embodiment of the present disclosure.

FIG. 4 is a sectional view of the stator vane on a plane including a camber line according to the first embodiment of the present disclosure.

FIG. 5 is a sectional view taken along line V-V in FIG. 4.

FIG. 6 is a perspective view of an insert according to the first embodiment of the present disclosure.

FIG. 7 is a sectional view of a stator vane on a plane perpendicular to an axis according to a second embodiment of the present disclosure.

FIG. 8 is a sectional view taken along line VIII-VIII in FIG. 7.

FIG. 9 is a sectional view of a stator vane on a plane including a camber line according to a first modification example of the first embodiment of the present disclosure.

FIG. 10 is a sectional view of a stator vane on a plane including a camber line according to a second modification example of the first embodiment of the present disclosure.

FIG. 11 is a sectional view of a stator vane on a plane including a camber line according to a third modification example of the first embodiment of the present disclosure.

DESCRIPTION OF EMBODIMENTS

Hereinafter, various embodiments of the present invention and modification examples thereof will be described in detail with reference to the drawings.

[Embodiment of Gas Turbine]

An embodiment of a gas turbine will be described with reference to FIGS. 1 and 2.

As illustrated in FIG. 1, a gas turbine **10** of the present embodiment includes a compressor **20** that compresses air A ; a combustor **30** that combusts a fuel F in the air A compressed by the compressor **20** to generate a combustion gas G ; and a turbine **40** driven by the combustion gas G .

The compressor **20** includes a compressor rotor **21** that rotates around an axis Ar ; a compressor casing **25** that covers the compressor rotor **21**; and a plurality of stator vane rows **26**. The turbine **40** includes a turbine rotor **41** that rotates around the axis Ar ; a turbine casing **45** that covers the turbine rotor **41**; and a plurality of stator vane rows **46**. Hereinafter, an extending direction of the axis Ar will be referred to as an axial direction Da , a circumferential direction around the axis Ar will be simply referred to as a circumferential direction Dc , and a direction perpendicular to the axis Ar will be referred to as a radial direction Dr . In addition, one side in the axial direction Da will be referred to as an axial upstream side Dau , and a side opposite thereto will be referred to as an axial downstream side Dad . In addition, a side closer to the axis Ar in the radial direction Dr will be referred to as a radial inner side Dri , and a side opposite thereto will be referred to as a radial outer side Dro .

The compressor **20** is disposed on the axial upstream side Dau with respect to the turbine **40**.

The compressor rotor **21** and the turbine rotor **41** are located on the same axis Ar , and are connected to each other to form a gas turbine rotor **11**. For example, a rotor of a generator **GEN** is connected to the gas turbine rotor **11**. The gas turbine **10** further includes an intermediate casing **16**. The intermediate casing **16** is disposed between the compressor casing **25** and the turbine casing **45** in the axial direction Da . The compressor casing **25**, the intermediate casing **16**, and the turbine casing **45** are connected to each other to form a gas turbine casing **15**.

The compressor rotor **21** includes a rotor shaft **22** extending in the axial direction Da around the axis Ar , and a plurality of rotor blade rows **23** attached to the rotor shaft **22**. The plurality of rotor blade rows **23** are aligned in the axial direction Da . Each of the rotor blade rows **23** is formed of a plurality of rotor blades **23a** aligned in the circumferential direction Dc . One stator vane row **26** of the plurality of stator vane rows **26** is disposed on the axial downstream side Dad of each of the plurality of rotor blade rows **23**. Each of the stator vane rows **26** is provided inside the compressor casing **25**. Each of the stator vane rows **26** is formed of a plurality of stator vanes **26a** aligned in the circumferential direction Dc .

As illustrated in FIGS. 1 and 2, the turbine rotor **41** includes a rotor shaft **42** extending in the axial direction Da around the axis Ar , and a plurality of rotor blade rows **43** attached to the rotor shaft **42**. The plurality of rotor blade rows **43** are aligned in the axial direction Da . Each of the rotor blade rows **43** is formed of a plurality of rotor blades **43a** aligned in the circumferential direction Dc . One stator vane row **46** of the plurality of stator vane rows **46** is disposed on the axial upstream side Dau of each of the plurality of rotor blade rows **43**. Each of the stator vane rows **46** is provided inside the turbine casing **45**. Each of the stator vane rows **46** is formed of a plurality of stator vanes **46a** aligned in the circumferential direction Dc .

The turbine casing **45** includes a tubular outer casing **45a** forming an outer shell thereof, an inner casing **45b** fixed to the inside of the outer casing **45a**, and a plurality of ring segments **45c** fixed to the inside of the inner casing **45b**.

Each of the plurality of ring segments **45c** is provided at a position between the plurality of stator vane rows **46**. Therefore, the rotor blade row **43** is disposed on the radial inner side **Dri** of each of the ring segments **45c**.

An annular space formed between an outer peripheral side of the rotor shaft **42** and an inner peripheral side of the turbine casing **45**, in which the stator vane **46a** and the rotor blade **43a** are disposed in the axial direction **Da**, forms a combustion gas passage **49** through which the combustion gas **G** from the combustors **30** flows.

The combustor **30** is attached to the intermediate casing **16**.

As illustrated in FIG. 1, the compressor **20** compresses the air **A** to generate compressed air. The compressed air flows into the combustor **30**. The fuel **F** is supplied to the combustor **30**. Inside the combustor **30**, the fuel **F** is combusted in the compressed air to generate the high-temperature and high-pressure combustion gas **G**. The combustion gas **G** is fed from the combustor **30** to the combustion gas passage **49** inside the turbine **40**. The combustion gas **G** rotates the turbine rotor **41** in a process of flowing through the combustion gas passage **49** to the axial downstream side **Dad**. A rotor of the generator **GEN** connected to the gas turbine rotor **11** is rotated by rotation of the turbine rotor **41**. As a result, the generator **GEN** generates electricity.

Hereinafter, various embodiments relating to the stator vane forming a first-stage stator vane row **46** will be described.

[First Embodiment of Stator Vane]

A first embodiment of the stator vane according to the present invention will be described with reference to FIGS. 3 to 6.

As illustrated in FIG. 3, a stator vane **50** of the present embodiment includes a blade body **51**, an inner shroud **60i**, and an outer shroud **60o**. A shape of a cross section of the blade body **51** has a blade shape, and the blade body **51** extends in a blade-height direction **Dh** having a direction component perpendicular to the cross section. The inner shroud **60i** is provided in an end on one side in the blade-height direction **Dh** in the blade body **51**. The outer shroud **60o** is provided in an end on the other side in the blade-height direction **Dh** in the blade body **51**. The blade body **51**, the inner shroud **60i**, and the outer shroud **60o** are integrally formed by casting or the like.

The blade-height direction is the radial direction **Dr** in a state where the stator vane **50** is attached to the turbine casing **45** (refer to FIG. 2). In addition, a blade-height first side **Dh1** on one side in the blade-height direction **Dh** is the radial inner side **Dri**, and a blade-height second side **Dh2** on the other side in the blade-height direction **Dh** is the radial outer side **Dro**. Therefore, the inner shroud **60i** is provided on the radial inner side **Dri** of the blade body **51**, and the outer shroud **60o** is provided on the radial outer side **Dro** of the blade body **51**. Therefore, in the present embodiment, in some cases, the blade-height direction **Dh** may be referred to as the radial direction **Dr**, the blade-height first side **Dh1** may be referred to as the radial inner side **Dri**, and the blade-height second side **Dh2** may be referred to as the radial outer side **Dro**.

As illustrated in FIGS. 3 to 5, a blade surface which is an outer surface of the blade body **51** includes a leading edge **52**, a trailing edge **53**, a suction surface **54** which is a convex surface, and a pressure surface **55** which is a concave surface. The leading edge **52** and the trailing edge **53** exist in a connecting portion between the suction surface **54** and the pressure surface **55**. The leading edge **52**, the trailing edge **53**, the suction surface **54**, and the pressure surface **55**

all extend in the radial direction **Dr** which is the blade-height direction **Dh**. The leading edge **52** is located on the axial upstream side **Dau** with respect to the trailing edge **53** in a state where the stator vane **50** is attached to the turbine casing **45**. In addition, in a state where the stator vane **50** is attached to the turbine casing **45**, the suction surface **54** faces a circumferential suction side **Dcn** which is one side in the circumferential direction **Dc**, and the pressure surface **55** faces a circumferential pressure side **Dcp** which is the other side in the circumferential direction **Dc**.

The blade body **51** is disposed inside the combustion gas passage **49** through which the combustion gas **G** passes. The blade body **51** includes a plurality of blade air passages **80** extending in the radial direction **Dr** inside the blade body **51**. The inner shroud **60i** defines an edge on the radial inner side **Dri** of the annular combustion gas passage **49**. In addition, the outer shroud **60o** defines an edge on the radial outer side **Dro** of the annular combustion gas passage **49**.

The inner shroud **60i** includes a shroud body **61**, a peripheral wall **71**, and a retainer **76**.

The shroud body **61** is a plate-shaped member that spreads in a direction including a direction component in a direction perpendicular to the radial direction **Dr** which is the blade-height direction **Dh**. The shroud body **61** includes a gas path surface **64**, a counter-gas path surface **65**, a front end surface **62f**, a rear end surface **62b**, a suction side end surface **63n**, and a pressure side end surface **63p**.

The gas path surface **64** is a surface facing the radial outer side **Dro** which is the blade-height second side **Dh2**, with which the combustion gas **G** comes into contact. The counter-gas path surface **65** is a surface facing the radial inner side **Dri** which is the blade-height first side **Dh1**. The counter-gas path surface **65** has a back-to-back relationship with the gas path surface **64**. The front end surface **62f** is a surface located closer to the axial upstream side **Dau** than the blade body **51** is, and facing the axial upstream side **Dau**. The rear end surface **62b** is a surface located closer to the axial downstream side **Dad** than the blade body **51** is, and facing the axial downstream side **Dad**. The suction side end surface **63n** is a surface located closer to the circumferential suction side **Dcn** than the blade body **51** is in the shroud body **61** and facing the circumferential suction side **Dcn**. The suction side end surface **63n** connects the front end surface **62f** and the rear end surface **62b**. The pressure side end surface **63p** is a surface located closer to the circumferential pressure side **Dcp** than the blade body **51** is in the shroud body **61** and facing the circumferential pressure side **Dcp**. The pressure side end surface **63p** connects the front end surface **62f** and the rear end surface **62b**. The rear end surface **62b** is located at an interval from the front end surface **62f** to the axial downstream side, and is substantially parallel to the front end surface **62f**. In addition, the pressure side end surface **63p** is located at an interval from the suction side end surface **63n** to one side in the circumferential direction **Dc**, and is substantially parallel to the suction side end surface **63n**. Therefore, when viewed in the radial direction **Dr**, the shroud body **61** has a parallel quadrilateral shape.

The peripheral wall **71** is a wall protruding from the shroud body **61** to the radial inner side **Dri** along an outer peripheral edge of the shroud body **61**. The peripheral wall **71** includes a front peripheral wall **71f** and a rear peripheral wall **71b** which face each other in the axial direction **Da**, and a pressure side peripheral wall **71p** and a suction side peripheral wall **71n** which face each other in the circumferential direction **Dc**. The front peripheral wall **71f** is located closer to the axial upstream side **Dau** than the blade body **51**

is. A surface of the front peripheral wall 71f facing the axial upstream side Dau forms a portion of the front end surface 62f of the inner shroud 60i. The rear peripheral wall 71b is located closer to the axial downstream side Dad than the blade body 51 is. The pressure side peripheral wall 71p is located closer to the circumferential pressure side Dcp than the blade body 51 is. A surface of the pressure side peripheral wall 71p facing the circumferential pressure side Dcp forms a portion of the pressure side end surface 63p of the inner shroud 60i. The suction side peripheral wall 71n is located closer to the circumferential suction side Dcn than the blade body 51 is. A surface of the suction side peripheral wall 71n facing the circumferential suction side Dcn forms a portion of the suction side end surface 63n of the inner shroud 60i.

In the inner shroud 60i, a cavity 72 recessed toward the radial inner side Dri is formed by the shroud body 61 and the peripheral wall 71. The cavity 72 is defined by the counter-gas path surface 65 of the shroud body 61, a surface of the front peripheral wall 71f facing the axial downstream side Dad, a surface of the rear peripheral wall 71b facing the axial upstream side Dau, a surface of the pressure side peripheral wall 71p facing the circumferential suction side Dcn, and a surface of the suction side peripheral wall 71n facing the circumferential pressure side Dcp.

The retainer 76 is located between the front peripheral wall 71f and the rear peripheral wall 71b in the axial direction Da, and is formed from the suction side end surface 63n to the pressure side end surface 63p. The retainer 76 is connected to an end 17a (refer to FIGS. 2 and 4) on the radial outer side Dro of an inner cover 17 fixed to the gas turbine casing 15, and serves to support a portion on the radial inner side Dri of the stator vane 50 on the inner cover 17.

The outer shroud 60o has essentially the same configuration as the configuration of the inner shroud 60i. Therefore, as in the inner shroud 60i, the outer shroud 60o also includes the shroud body 61 and the peripheral wall 71. However, the outer shroud 60o does not have a portion corresponding to the retainer 76 of the inner shroud 60i. As in the shroud body 61 of the inner shroud 60i, the shroud body 61 of the outer shroud 60o also includes the gas path surface 64, the counter-gas path surface 65, the front end surface 62f, the rear end surface 62b, the suction side end surface 63n, and the pressure side end surface 63p. In addition, as in the peripheral wall 71 of the inner shroud 60i, the peripheral wall 71 of the outer shroud 60o also includes the front peripheral wall 71f, the rear peripheral wall 71b, the pressure side peripheral wall 71p, and the suction side peripheral wall 71n. The front peripheral wall 71f and the rear peripheral wall 71b of the outer shroud 60o serve to attach the stator vane 50 to an inner peripheral side of the turbine casing 45 (refer to FIG. 2).

As illustrated in FIGS. 3 and 5, the plurality of blade air passages 80 formed inside the blade body 51 are aligned along a camber line CL of the blade body 51. Here, in the plurality of blade air passages 80, the blade air passage 80 closest to the axial upstream side Dau will be referred to as a front side blade air passage 80f, and the blade air passage 80 closest to the axial downstream side Dad will be referred to as a rear side blade air passage 80b. In addition, in the plurality of blade air passages 80, two blade air passages 80 between the front side blade air passage 80f and the rear side blade air passage 80b will be referred to as intermediate blade air passages 80m. Furthermore, out of the two intermediate blade air passages 80m, the intermediate blade air passage 80m on the axial upstream side Dau will be referred to as a first blade air passage 81, and the intermediate blade

air passage 80m on the axial downstream side Dad will be referred to as a second blade air passage 85.

In the front side blade air passage 80f, an end on the radial inner side Dri which is the blade-height first side Dh1 is closed, and an end on the radial outer side Dro which is the blade-height second side Dh2 is open. A plurality of front side ejection holes 80fa penetrating from the front side blade air passage 80f to the combustion gas passage 49 are formed in a front side portion including the leading edge 52 of the blade body 51. An end on the radial inner side Dri of the blade body 51 forms a portion of the counter-gas path surface 65 of the inner shroud 60i, and an end on the radial outer side Dro of the blade body 51 forms a portion of the counter-gas path surface 65 of the outer shroud 60o. Therefore, an opening 80fo of the front side blade air passage 80f is open on the counter-gas path surface 65 of the outer shroud 60o.

In the rear side blade air passage 80b, an end on the radial inner side Dri which is the blade-height first side Dh1 is closed, and an end on the radial outer side Dro which is the blade-height second side Dh2 is open. An opening 80bo of the rear side blade air passage 80b is open on the counter-gas path surface 65 of the outer shroud 60o. A plurality of rear side ejection holes 80ba penetrating from the rear side blade air passage 80b to the combustion gas passage 49 are formed in a rear side portion including the trailing edge 53 of the blade body 51.

In the first blade air passage 81, an end on the radial inner side Dri which is the blade-height first side Dh1, and an end on the radial outer side Dro which is the blade-height second side Dh2 are open. A first opening 82f which is an opening on the blade-height first side Dh1 of the first blade air passage 81 is open on the counter-gas path surface 65 of the inner shroud 60i. In addition, a second opening 82s which is an opening on the blade-height second side Dh2 of the first blade air passage 81 is open on the counter-gas path surface 65 of the outer shroud 60o. The blade body 51 has a plurality of pressure side first ejection holes 83pf penetrating from a first passage defining surface 81p defining the first blade air passage 81 of the blade body 51 to a pressure side first blade surface portion 55f which is a portion of the pressure surface 55. The pressure side first blade surface portion 55f is a portion having a back-to-back relationship with the first blade air passage 81 on the pressure surface 55 of the blade body 51. In addition, the blade body 51 has a plurality of suction side first ejection holes 83nf penetrating from the first passage defining surface 81p defining the first blade air passage 81 of the blade body 51 to a suction side first blade surface portion 54f which is a portion of the suction surface 54. The suction side first blade surface portion 54f is a portion having a back-to-back relationship with the first blade air passage 81 on the suction surface 54 of the blade body 51.

In the second blade air passage 85, an end on the radial inner side Dri which is the blade-height first side Dh1 is closed, and an end on the radial outer side Dro which is the blade-height second side Dh2 is open. An opening 86 of the second blade air passage 85 is open on the counter-gas path surface 65 of the outer shroud 60o. The blade body 51 has a plurality of pressure side second ejection holes 87ps penetrating from a second passage defining surface 85p defining the second blade air passage 85 of the blade body 51 to a pressure side second blade surface portion 55s which is a portion of the pressure surface 55.

The pressure side second blade surface portion 55s is a portion having a back-to-back relationship with the second blade air passage 85 on the pressure surface 55 of the blade

body 51. In addition, the blade body 51 has a plurality of suction side second ejection holes 87ns penetrating from the second passage defining surface 85p defining the second blade air passage 85 of the blade body 51 to a suction side second blade surface portion 54s which is a portion of the suction surface 54. The suction side second blade surface portion 54s is a portion having a back-to-back relationship with the second blade air passage 85 on the suction surface 54 of the blade body 51.

As described above, in both the first blade air passage 81 and the second blade air passage 85, an end on the radial outer side D_{Ro} which is the blade-height second side D_{h2} is open.

In addition, as illustrated in FIGS. 3 to 6, the stator vane of the present embodiment further includes a first insert 90, a second insert 95, an end cover 100, a plurality of first guide members 110, and a second guide member 115.

The first insert 90 is disposed inside the first blade air passage 81, and the second insert 95 is disposed inside the second blade air passage 85. As illustrated in FIG. 6, the first insert 90 includes an outer peripheral plate portion 91, a sealing plate portion 93, and a flange portion 94. In addition, the second insert 95 includes an outer peripheral plate portion 96, a sealing plate portion 98, and a flange portion 99. The outer peripheral plate portions 91 and 96 of the first insert 90 and the second insert 95 have a tubular shape, and extend in a tube-height direction D_h. Here, out of two sides in the tube-height direction D_h, one side will be referred to as a tube-height sealing side D_{h1}, and the other side will be referred to as a tube-height opening side D_{h2}. The sealing plate portions 93 and 98 close ends of the outer peripheral plate portions 91 and 96 on the tube-height sealing side D_{h1}. Meanwhile, the sealing plate portion is not provided in end portions of the outer peripheral plate portions 91 and 96 on the tube-height opening side D_{h2}. Therefore, insert openings 90o and 95o for introducing the cooling air into the outer peripheral plate portions 91 and 96 are formed in the end portions of the outer peripheral plate portions 91 and 96 on the tube-height opening side D_{h2}. The flange portions 94 and 99 spread toward the outer peripheral side from the ends on the tube-height opening side D_{h2} on all of the outer peripheral surfaces of the outer peripheral plate portions 91 and 96.

The outer peripheral plate portion 91 of the first insert 90 is disposed inside the first blade air passage 81 so that the tube-height opening side D_{h2} faces the blade-height first side D_{h1} and a gap exists between the outer peripheral plate portion 91 and the first passage defining surface 81p of the blade body 51 defining the first blade air passage 81. The flange portion 94 is connected to an edge of the first opening 82f of the first blade air passage 81 to close the gap between the outer peripheral plate portion 91 and the first passage defining surface 81p. The gap between the outer peripheral side of the outer peripheral plate portion 91 of the first insert 90 and the first passage defining surface 81p forms an intra-blade first cavity C1 into which the cooling air Ac flows.

In the outer peripheral plate portion 91 of the first insert 90, a portion facing the pressure side first blade surface portion 55f and a portion facing the suction side first blade surface portion 54f have a plurality of impingement holes 92 penetrating from the inside to the outside of the outer peripheral plate portion 91.

The outer peripheral plate portion 96 of the second insert 95 is disposed inside the second blade air passage 85 so that the tube-height opening side D_{h2} faces the blade-height second side D_{h2}, and a gap exists between the outer peripheral plate portion 96 and the second passage defining surface 85p of the second blade air passage 85.

eral plate portion 96 and the second passage defining surface 85p of the blade body 51 defining the second blade air passage 85. The flange portion 99 is connected to an edge of the opening 86 of the second blade air passage 85 to close the gap between the outer peripheral plate portion 96 and the second passage defining surface 85p. The gap between the outer peripheral side of the outer peripheral plate portion 96 of the second insert 95 and the second passage defining surface 85p forms an intra-blade second cavity C2 into which the cooling air Ac flows.

In the outer peripheral plate portions 96 of the second insert 95, a portion facing the pressure side second blade surface portion 55s and a portion facing the suction side second blade surface portion 54s have a plurality of impingement holes 97 penetrating from the inside to the outside of the outer peripheral plate portion 96.

The second blade surface portions 54s and 55s on the blade surface are located closer to the axial downstream side D_{ad} than the first blade surface portions 54f and 55f are. Therefore, positions of the second blade surface portions 54s and 55s are positions where the pressure of the portions along the second blade surface portions 54s and 55s outside the blade body 51 is lower than the pressure of the portions along the first blade surface portions 54f and 55f outside the blade body 51, while the gas turbine 10 is driven.

The end cover 100 includes a top plate portion 101 and an outer peripheral plate portion 102. The outer peripheral plate portion 102 extends along an edge of the top plate portion 101 in a direction substantially perpendicular to the top plate portion 101. The end cover 100 is disposed on the blade-height second side D_{h2} of the blade body 51. The top plate portion 101 faces a region where the first blade air passage 81 and the second air passage are disposed on the counter-gas path surface 65 of the outer shroud 60o at an interval in the blade-height direction D_h. The outer peripheral plate portion 102 of the end cover 100 is connected to an edge of a region where the first blade air passage 81 and the second air passage exist on the counter-gas path surface 65 of the outer shroud 60o. Therefore, the end cover 100 can guide the cooling air Ac flowing out from the second opening 82s of the first blade air passage 81 into the second blade air passage 85 from the opening 86 of the second blade air passage 85.

As illustrated in FIG. 6, each of the plurality of first guide members 110 includes a first groove member 111 having a first groove 112 extending in the tube-height direction D_h, and a first convex member 113 entering the inside of the first groove 112 and relatively movable in the tube-height direction D_h with respect to the first groove 112. The plurality of first groove members 111 are fixed to the first passage defining surface 81p at an interval in the circumferential direction of the first passage defining surface 81p (refer to FIGS. 4 and 5). Each of the plurality of first convex members 113 is disposed to enter any one first groove 112 of the first grooves 112 of the plurality of first groove members 111, and is fixed to the outer peripheral plate portion 91 of the first insert 90. Therefore, the first guide member 110 allows displacement of the first insert 90 in the tube-height direction D_h, and regulates displacement of the first insert 90 in a direction perpendicular to the tube-height direction D_h.

As illustrated in FIG. 6, the second guide member 115 includes a second groove member 116 having a second groove 117 extending in the tube-height direction D_h, and a second convex member 118 entering the second groove 117 and relatively movable in the tube-height direction D_h with respect to the second groove 117. The second groove

member 116 is fixed to a bottom surface defining a surface of the second blade air passage 85 on the blade-height first side Dh1 on the second passage defining surface 85p (refer to FIG. 4). The second convex member 118 is disposed to enter the second groove 117 of the second groove member 116, and is fixed to the sealing plate portion 98 of the second insert 95. Therefore, the second guide member 115 allows displacement of the second insert 95 in the tube-height direction Dih, and regulates displacement of the second insert 95 in a direction perpendicular to the tube-height direction Dih.

The cooling air Ac flows into the cavity 72 of the outer shroud 60o from the radial outer side Dro of the outer shroud 60o. In addition, the cooling air Ac flows into the cavity 72 of the inner shroud 60i from the radial inner side Dri of the inner shroud 60i. For example, as the cooling air Ac, air compressed by the compressor 20 is used.

The cooling air Ac flowing into the cavity 72 of the outer shroud 60o cools the outer shroud 60o. In particular, the cooling air Ac cools the gas path surface of the outer shroud 60o.

A portion of the cooling air Ac flowing into the cavity 72 of the outer shroud 60o flows into the front side blade air passage 80f from the opening 80fo of the front side blade air passage 80f. The cooling air Ac performs convection cooling on a portion around the front side blade air passage 80f in the blade body 51. Furthermore, the cooling air Ac is ejected into the combustion gas passage 49 from the plurality of front side ejection holes 80fa toward the axial upstream side Dau. In a process of flowing through the plurality of front side ejection holes 80fa, the cooling air Ac performs convection cooling on a portion around the plurality of front side ejection holes 80fa. A portion of the cooling air Ac ejected into the combustion gas passage 49 prevents a front portion of the blade surface including the leading edge 52 of the blade body 51 from being exposed to the combustion gas G, and prevents the front portion of the blade surface from being heated by the combustion gas G.

The other portion of the cooling air Ac flowing into the cavity 72 of the outer shroud 60o flows into the rear side blade air passage 80b from the opening 80bo of the rear side blade air passage 80b. The cooling air Ac performs convection cooling on a portion around the rear side blade air passage 80b in the blade body 51. Furthermore, the cooling air Ac is ejected into the combustion gas passage 49 from the plurality of rear side ejection holes 80ba toward the axial downstream side Dad. In a process of flowing through the plurality of rear side ejection holes 80ba, the cooling air Ac performs convection cooling on a portion around the plurality of rear side ejection holes 80ba. A portion of the cooling air Ac ejected into the combustion gas passage 49 prevents a rear portion of the blade surface including the trailing edge 53 of the blade body 51 from being exposed to the combustion gas G, and prevents the rear portion of the blade surface from being heated by the combustion gas G. Furthermore, a portion of the cooling air Ac ejected into the combustion gas passage 49 prevents a vortex flow from being formed on the axial downstream side Dad of the blade body 51.

The cooling air Ac flowing into the cavity 72 of the inner shroud 60i cools the inner shroud 60i. In particular, the cooling air Ac cools the gas path surface 64 of the inner shroud 60i.

The cooling air Ac flowing into the cavity 72 of the inner shroud 60i flows into the outer peripheral plate portion 91 of the first insert 90 from the first opening 82f of the first blade air passage 81 and the insert opening 90o of the first insert

90. The cooling air Ac flowing into the outer peripheral plate portion 91 is ejected to the outer peripheral side of the outer peripheral plate portion 91 from the plurality of impingement holes 92 formed in the outer peripheral plate portion 91, and flows into the intra-blade first cavity C1. The cooling air Ac collides with a portion having a back-to-back relationship with the pressure side first blade surface portion 55f and a portion having a back-to-back relationship with the suction side first blade surface portion 54f on the first passage defining surface 81p, and performs impingement cooling on these portions. The impingement cooling has a higher cooling effect on a cooling target, compared to the convection cooling. A distance between an ejection port of the cooling air Ac and a surface with which the cooling air Ac ejected from the ejection port collides affects a cooling effect in the impingement cooling. Therefore, the present embodiment is provided with the first guide member 110 that regulates the displacement of the first insert 90 in the direction perpendicular to the tube-height direction Dih while allowing the displacement of the first insert 90 in the tube-height direction Dih.

In the present embodiment, the first groove member 111 of the first guide member 110 is fixed to the first passage defining surface 81p, and the first convex member 113 of the first guide member 110 is fixed to the outer peripheral plate portion 91 of the first insert 90. However, the first groove member 111 may be fixed to the outer peripheral plate portion 91 of the first insert 90, and the first convex member 113 may be fixed to the first passage defining surface 81p. In addition, one member of the first groove member 111 and the first convex member 113 may be fixed to the first insert 90, and the other member may be fixed to the end cover 100. However, the end cover 100 has a lower rigidity, compared to the blade body 51. Therefore, from a viewpoint of regulating the displacement of the first insert 90 in the direction perpendicular to the tube-height direction Dih, it is preferable to fix the other member to a side of the blade body 51.

A portion of the cooling air Ac flowing into the intra-blade first cavity C1 is ejected into the combustion gas passage 49 from the plurality of pressure side first ejection holes 83pf and the plurality of suction side first ejection holes 83nf. The cooling air Ac ejected from the plurality of pressure side first ejection holes 83pf performs film cooling mainly on a downstream side portion of the pressure side first blade surface portion 55f on the blade surface. In addition, the cooling air Ac ejected from the plurality of suction side first ejection holes 83nf performs film cooling mainly on a downstream side portion of the suction side first blade surface portion 54f on the blade surface.

The remaining portion of the cooling air Ac flowing into the intra-blade first cavity C1 flows inside the intra-blade first cavity C1 toward the radial outer side Dro which is the blade-height second side Dh2, flows out from the second opening 82s of the first blade air passage 81, and flows into the end cover 100. The cooling air Ac performs the convection cooling around the intra-blade first cavity C1 in the blade body 51 in a process of flowing inside the intra-blade first cavity C1.

The cooling air Ac flowing into the end cover 100 flows into the outer peripheral plate portion 96 of the second insert 95 from the opening 86 of the second blade air passage 85 and the insert opening 95o of the second insert 95. The cooling air Ac flowing into the outer peripheral plate portion 96 is ejected to the outer peripheral side of the outer peripheral plate portion 96 from the plurality of impingement holes 97 formed in the outer peripheral plate portion

96, and flows into the intra-blade second cavity C2. The cooling air Ac collides with a portion having a back-to-back relationship with the pressure side second blade surface portion 55s and a portion having a back-to-back relationship with the suction side second blade surface portion 54s on the second passage defining surface 85p, and performs the impingement cooling on these portions. As described above, a distance between the ejection port of the cooling air Ac and the surface with which the cooling air Ac ejected from the ejection port collides affects the cooling effect in the impingement cooling. Therefore, the present embodiment is provided with the first guide member 110 that regulates the displacement of the second insert 95 in the direction perpendicular to the tube-height direction Dih while allowing the displacement of the second insert 95 in the tube-height direction Dih.

In the present embodiment, the second groove member 116 of the second guide member 115 is fixed to the second passage defining surface 85p, and the second convex member 118 of the second guide member 115 is fixed to the sealing plate portion 98 of the second insert 95. However, the second groove member 116 may be fixed to the sealing plate portion 98 of the second insert 95, and the second convex member 118 may be fixed to the second passage defining surface 85p.

The cooling air Ac flowing into the intra-blade second cavity C2 is ejected into the combustion gas passage 49 from the plurality of pressure side second ejection holes 87ps and the plurality of suction side second ejection holes 87ns. The cooling air Ac ejected from the plurality of pressure side second ejection holes 87ps performs the film cooling mainly on a downstream side portion of the pressure side second blade surface portion 55s on the blade surface. In addition, the cooling air Ac ejected from the plurality of suction side second ejection holes 87ns performs the film cooling mainly on a downstream side portion of the suction side second blade surface portion 54s on the blade surface.

As described above, in the present embodiment, the cooling air Ac flowing into the first insert 90 disposed inside the first blade air passage 81 performs the impingement cooling on the first passage defining surface 81p. Furthermore, a portion of the cooling air Ac performs the film cooling on the downstream side portion of the pressure side first blade surface portion 55f and the downstream side portion of the suction side second blade surface portion 54s, and the remaining portion of the cooling air Ac performs the convection cooling around the intra-blade first cavity C1 in the blade body 51 in a process of flowing inside the intra-blade first cavity C1. In the present embodiment, the remaining portion of the cooling air Ac flows into the second insert 95 disposed inside the second blade air passage 85. The cooling air Ac flowing into the second insert 95 performs the impingement cooling on the second passage defining surface 85p. Furthermore, the cooling air Ac performs the film cooling on the downstream side portion of the pressure side second blade surface portion 55s and the downstream side portion of the suction side second blade surface portion 54s. Therefore, in the present embodiment, the stator vane 50 can be more efficiently cooled, and a usage amount of the cooling air Ac can be reduced, compared to when the cooling air Ac flowing into one insert is ejected to the combustion gas passage immediately after the cooling air Ac performs the impingement cooling on the inside of the blade body.

[Second Embodiment of Stator Vane]

Hereinafter, a second embodiment of the stator vane according to the present invention will be described with

reference to FIGS. 7 and 8. FIG. 7 is a sectional view taken along a plane perpendicular to the axis Ar of the stator vane. In addition, FIG. 8 is a sectional view taken along line VIII-VIII in FIG. 7.

As illustrated in FIG. 7, a stator vane 50a of the present embodiment also includes a blade body 51a, the inner shroud 60i, and the outer shroud 60o. The inner shroud 60i and the outer shroud 60o of the present embodiment are the same as the inner shroud 60i and the outer shroud 60o of the first embodiment.

As illustrated in FIGS. 7 and 8, as in the blade body 51 of the first embodiment, the plurality of blade air passages 80 are formed in the blade body 51a of the present embodiment. In the plurality of blade air passages 80, the blade air passage 80 closest to the axial upstream side Dau forms the front side blade air passage 80f, and the blade air passage 80 closest to the axial downstream side Dad forms the rear side blade air passage 80b. The configuration of the front side blade air passage 80f is the same as the configuration of the front side blade air passage 80f of the first embodiment. In addition, the configuration of the rear side blade air passage 80b is the same as the configuration of the rear side blade air passage 80b of the first embodiment. In addition, in the plurality of blade air passages 80, two blade air passages 80 between the front side blade air passage 80f and the rear side blade air passage 80b form intermediate blade air passages 80ma. The two intermediate blade air passages 80ma are aligned in the circumferential direction Dc, unlike the two intermediate blade air passages 80m of the first embodiment. Here, in the two intermediate blade air passages 80ma, the intermediate blade air passage 80ma on the circumferential pressure side Dcp will be referred to as a first blade air passage 81a, and the intermediate blade air passage 80ma on the circumferential suction side Dcn will be referred to as a second blade air passage 85a.

In the first blade air passage 81a, an end on the radial inner side Dri which is the blade-height first side Dh1 and an end on the radial outer side Dro which is the blade-height second side Dh2 are open. The first opening 82f which is an opening on the radial inner side Dri of the first blade air passage 81a is open on the counter-gas path surface 65 of the inner shroud 60i. In addition, the second opening 82s which is an opening on the radial outer side Dro of the first blade air passage 81a is open on the counter-gas path surface 65 of the outer shroud 60o. The blade body 51a has a plurality of pressure side first ejection holes 83pf penetrating from the first passage defining surface 81p defining the first blade air passage 81a of the blade body 51a to the pressure side first blade surface portion 55f which is a portion of the pressure surface 55. The pressure side first blade surface portion 55f is a portion having a back-to-back relationship with the first blade air passage 81a on the pressure surface 55 of the blade body 51a.

In the second blade air passage 85a, an end on the radial inner side Dri which is the blade-height first side Dh1 is closed, and an end on the radial outer side Dro which is the blade-height second side Dh2 is open. The opening 86 of the second blade air passage 85a is open on the counter-gas path surface 65 of the outer shroud 60o. The blade body 51a has a plurality of suction side second ejection holes 87ns penetrating from the second passage defining surface 85p defining the second blade air passage 85a of the blade body 51a to the suction side second blade surface portion 54s which is a portion of the suction surface 54. The suction side second blade surface portion 54s is a portion having a back-to-back relationship with the second blade air passage 85a on the suction surface 54 of the blade body 51a.

In the present embodiment, in both the first blade air passage **81a** and the second blade air passage **85a**, the end on the radial outer side **Dro** which is the blade-height second side **Dh2** is also open.

The stator vane **50a** of the present embodiment also further includes a first insert **90a**, a second insert **95a**, an end cover **100a**, the plurality of first guide members **110**, and the second guide member **115**.

The first insert **90a** is disposed inside the first blade air passage **81a**, and the second insert **95a** is disposed inside the second blade air passage **85a**. As in the first insert **90** of the first embodiment, the first insert **90a** includes the outer peripheral plate portion **91**, the sealing plate portion **93**, and the flange portion **94**. In addition, as in the second insert **95** of the first embodiment, the second insert **95a** includes the outer peripheral plate portion **96**, the sealing plate portion **98**, and the flange portion **99**. The outer peripheral plate portions **91** and **96** of the first insert **90a** and the second insert **95a** form a tubular shape, and extend in the tube-height direction **Dih**. The sealing plate portions **93** and **98** close ends of the outer peripheral plate portions **91** and **96** on the tube-height sealing side **Dih1**. Meanwhile, the sealing plate portion is not provided in end portions of the outer peripheral plate portions **91** and **96** on the tube-height opening side **Dih2**. Therefore, the insert openings **90o** and **95o** for introducing the cooling air **Ac** into the outer peripheral plate portions **91** and **96** are formed in end portions of the outer peripheral plate portions **91** and **96** on the tube-height opening side **Dih2**. The flange portions **94** and **99** spread toward the outer peripheral side from the ends on the tube-height opening side **Dih2** on all of the outer peripheral surfaces of the outer peripheral plate portions **91** and **96**.

The outer peripheral plate portion **91** of the first insert **90a** is disposed inside the first blade air passage **81a** so that the tube-height opening side **Dih2** faces the blade-height first side **Dh1**, and a gap exists between the outer peripheral plate portion **91** and the first passage defining surface **81p** of the blade body **51a** defining the first blade air passage **81a**. The flange portion **94** is connected to an edge of the first opening **82f** of the first blade air passage **81a** to close the gap between the outer peripheral plate portion **91** and the first passage defining surface **81p**. The gap between the outer peripheral side of the outer peripheral plate portion **91** of the first insert **90a** and the first passage defining surface **81p** forms the intra-blade first cavity **C1** into which the cooling air **Ac** flows.

The plurality of impingement holes **92** penetrating from the inside to the outside of the outer peripheral plate portion **91** are formed in a portion facing the pressure side first blade surface portion **55f** in the outer peripheral plate portion **91** of the first insert **90a**.

The outer peripheral plate portion **96** of the second insert **95a** is disposed inside the second blade air passage **85a** so that the tube-height opening side **Dih2** faces the blade-height second side **Dh2**, and a gap exists between the outer peripheral plate portions **91** and **96** and the second passage defining surface **85p** of the blade body **51a** defining the second blade air passage **85a**. The flange portions **94** and **99** are connected to the edge of the opening of the second blade air passage **85a** to close the gap between the outer peripheral plate portions **91** and **96** and the second passage defining surface **85p**. The gap between the outer peripheral side of the outer peripheral plate portions **91** and **96** of the second insert **95a** and the second passage defining surface **85p** forms the intra-blade second cavity **C2** into which the cooling air **Ac** flows.

The plurality of impingement holes **97** penetrating from the inside to the outside of the outer peripheral plate portion **96** are formed in a portion facing the suction side second blade surface portion **54s** in the outer peripheral plate portion **96** of the second insert **95a**.

The second blade surface portion **54s** is a portion of the suction surface **54**, and the first blade surface portion **55f** is a portion of the pressure surface **55**. Therefore, a position of the second blade surface portion **54s** is a position where the pressure of the portion along the second blade surface portion **54s** outside the blade body **51a** is lower than the pressure of the portion along the first blade surface portion **55f** outside the blade body **51a**, while the gas turbine **10** is driven.

As in the end cover **100** of the first embodiment, the end cover **100a** includes a top plate portion **101a** and the outer peripheral plate portion **102**. However, in the present embodiment, an alignment direction of the second blade air passage **85a** with respect to the first blade air passage **81a** is different from that in the first embodiment. Therefore, a shape of the top plate portion **101a** is different from a shape of the top plate portion **101** of the first embodiment. As in the end cover **100** of the first embodiment, the end cover **100a** can also guide the cooling air **Ac** flowing out from the second opening **82s** of the first blade air passage **81a** into the second blade air passage **85a** from the opening **86** of the second blade air passage **85a**.

The first guide member **110** is the same as the first guide member **110** of the first embodiment. In addition, the second guide member **115** is the same as the second guide member **115** of the first embodiment.

A flow of the cooling air **Ac** of the present embodiment is the same as a flow of the cooling air **Ac** of the first embodiment. Therefore, in the present embodiment, the cooling air **Ac** flowing into the first insert **90a** disposed inside the first blade air passage **81a** also performs the impingement cooling on the first passage defining surface **81p**. Furthermore, a portion of the cooling air **Ac** performs the film cooling on a downstream side portion of the pressure side first blade surface portion **55f**, and the remaining portion performs the convection cooling around the intra-blade first cavity **C1** in the blade body **51a** in a process of flowing inside the intra-blade first cavity **C1**. The remaining portion of the cooling air **Ac** flows into the second insert **95a** disposed inside the second blade air passage **85a**. The cooling air **Ac** flowing into the second insert **95a** performs the impingement cooling on the second passage defining surface **85p**. Furthermore, the cooling air **Ac** performs the film cooling on a downstream side portion of the suction side second blade surface portion **54s**. Therefore, in the present embodiment, the stator vane **50a** can be more efficiently cooled, and a usage amount of the cooling air **Ac** can be reduced, compared to when the cooling air **Ac** flowing into one insert is ejected to the combustion gas passage immediately after the cooling air **Ac** performs the impingement cooling on the inside of the blade body.

As described above, as in the first embodiment, the second blade air passage may be disposed on the axial downstream side **Dad** of the first blade air passage **81**, or as in the present embodiment, the second blade air passage may be disposed on the circumferential suction side **Dcn** of the first blade air passage **81a**.

[First Modification Example of Stator Vane]

Hereinafter, a first modification example of the first embodiment of the stator vane according to the present invention will be described with reference to FIG. 9.

A stator vane **50b** of the present modification example is different from the stator vane **50** of the first embodiment in a shape and an attachment method of a first insert **90b** and a second insert **95b**, and other configurations are the same.

The first insert **90b** of the present modification example includes the outer peripheral plate portion **91**, the sealing plate portion **93**, and a flange portion **94b**. The outer peripheral plate portion **91** has a tubular shape, and extends in the tube-height direction **Dih**. The sealing plate portion **93** closes an end of the outer peripheral plate portion **91** on the tube-height sealing side **Dih1**. Meanwhile, the sealing plate portion is not provided in an end portion of the outer peripheral plate portion **91** on the tube-height opening side **Dih2**. Therefore, the insert opening **90o** for introducing the cooling air **Ac** into the outer peripheral plate portion **91** is formed in the end portion of the outer peripheral plate portion **91** on the tube-height opening side **Dih2**. Unlike the flange portion **94** of the first insert **90** in the first embodiment, the flange portion **94b** spreads toward the outer peripheral side from the end on the tube-height sealing side **Dih1** in a portion of the outer peripheral surface of the outer peripheral plate portion **91**. Therefore, the flange portion **94b** of the first insert **90b** has a shape in which a portion is cut out.

The outer peripheral plate portion **91** of the first insert **90b** is disposed inside the first blade air passage **81** so that the tube-height opening side **Dih2** faces the blade-height first side **Dh1**, and a gap exists between the outer peripheral plate portion **91** and the first passage defining surface **81p**. An outer edge of the flange portion **94b** is connected to the vicinity of the second opening **82s** of the first blade air passage **81**. Therefore, unlike the first insert **90** in the first embodiment, in the first insert **90b** of the present modification example, the tube-height sealing side **Dih1** is fixed to the blade body **51**. A seal flange **84** protruding toward a center side of the first blade air passage **81** and facing the outer peripheral plate portion **91** of the first insert **90b** is provided in an edge of the first opening **82f** of the first blade air passage **81**. The seal flange **84** serves to prevent the cooling air **Ac** flowing into the cavity **72** of the inner shroud **60i** from flowing into the intra-blade first cavity **C1** inside the first blade air passage **81**. The seal flange **84** is not fixed to the outer peripheral plate portion **91** of the first insert **90b** to allow the displacement of the first insert **90b** in the blade-height direction **Dh**.

In the outer peripheral plate portion **91** of the first insert **90b**, a portion facing the pressure side first blade surface portion **55f** and a portion facing the suction side first blade surface portion **54f** have the plurality of impingement holes **92** penetrating from the inside to the outside of the outer peripheral plate portion **91**, as in the outer peripheral plate portion **91** of the first insert **90** in the first embodiment.

The second insert **95b** of the present modification example includes the outer peripheral plate portion **96** and the sealing plate portion **98**, and does not include the flange portion. The outer peripheral plate portion **96** has a tubular shape, and extends in the tube-height direction **Dih**. The sealing plate portion **98** closes an end of the outer peripheral plate portion **96** on the tube-height sealing side **Dih1**. Meanwhile, the sealing plate portion is not provided in an end portion of the outer peripheral plate portion **96** on the tube-height opening side **Dih2**. Therefore, the insert opening **95o** for introducing the cooling air **Ac** into the outer peripheral plate portion **96** is formed in the end portion of the outer peripheral plate portion **96** on the tube-height opening side **Dih2**.

The outer peripheral plate portion **96** of the second insert **95b** is disposed inside the second blade air passage **85** so that the tube-height opening side **Dih2** faces the blade-height second side **Dh2**, and a gap exists between the outer peripheral plate portion **96** and the second passage defining surface **85p**. The sealing plate portion **98** of the second insert **95b** is fixed to a bottom surface which is a surface of the second blade air passage **85** on the blade-height first side **Dh1**, on the second passage defining surface **85p**. Therefore, unlike the second insert **95** in the first embodiment, in the second insert **95b** of the present modification example, the tube-height sealing side **Dih1** is fixed to the blade body **51**. A seal flange **88** protruding toward a center side of the second blade air passage **85** and facing the outer peripheral plate portion **96** of the second insert **95b** is provided in an edge of the opening **86** of the second blade air passage **85**. The seal flange **88** serves to prevent the cooling air **Ac** inside the end cover **100** from flowing into the intra-blade second cavity **C2** inside the second blade air passage **85**. The seal flange **88** is not fixed to the outer peripheral plate portion **96** of the second insert **95b** to allow the displacement of the second insert **95b** in the blade-height direction **Dh**.

In the outer peripheral plate portion **96** of the second insert **95b**, a portion facing the pressure side second blade surface portion **55s** and a portion facing the suction side second blade surface portion **54s** have the plurality of impingement holes **97** penetrating from the inside to the outside of the outer peripheral plate portion **96**, as in the outer peripheral plate portion **96** of the first insert **90** in the first embodiment.

In the present modification example, the cooling air **Ac** also flows into the cavity **72** of the outer shroud **60o** from the radial outer side **Dro** of the outer shroud **60o**. In addition, the cooling air **Ac** flows into the cavity **72** of the inner shroud **60i** from the radial inner side **Dri** of the inner shroud **60i**.

As in the first embodiment, a portion of the cooling air **Ac** flowing into the cavity **72** of the outer shroud **60o** flows into the front side blade air passage **80f** from the opening **80fo** of the front side blade air passage **80f**. In addition, as in the first embodiment, the other portion of the cooling air **Ac** flowing into the cavity **72** of the outer shroud **60o** also flows into the rear side blade air passage **80b** from the opening **80bo** of the rear side blade air passage **80b**.

Most of the cooling air **Ac** flowing into the cavity **72** of the inner shroud **60i** flows into the outer peripheral plate portion **91** of the first insert **90b** from the first opening **82f** of the first blade air passage **81** and the insert opening **90o** of the first insert **90b**. However, a slight amount of the cooling air **Ac** flowing into the cavity **72** of the inner shroud **60i** flows into the intra-blade first cavity **C1** inside the first blade air passage **81** from a gap between the seal flange **84** provided in an edge of the first opening **82f** of the first blade air passage **81** and the outer peripheral plate portion **91** of the first insert **90b**. The cooling air **Ac** flowing into the outer peripheral plate portion **91** is ejected to the outer peripheral side of the outer peripheral plate portion **91** from the plurality of impingement holes **92** formed in the outer peripheral plate portion **91**, and flows into the intra-blade first cavity **C1**. The cooling air **Ac** collides with a portion having a back-to-back relationship with the pressure side first blade surface portion **55f** and a portion having a back-to-back relationship with the suction side first blade surface portion **54f** on the first passage defining surface **81p**, and performs impingement cooling on these portions.

A portion of the cooling air **Ac** flowing into the intra-blade first cavity **C1** is ejected into the combustion gas passage **49** from the plurality of pressure side first ejection holes **83pf**.

and the plurality of suction side first ejection holes **83nf**. The remaining portion of the cooling air **Ac** flowing into the intra-blade first cavity **C1** flows inside the intra-blade first cavity **C1** toward the radial outer side **Dro** which is the blade-height second side **Dh2**, and flows into the end cover **100** through a cutout portion of the flange portion **94b** of the first insert **90b** and the second opening **82s** of the first blade air passage **81**.

Most of the cooling air **Ac** flowing into the end cover **100** flow into the outer peripheral plate portion **96** of the second insert **95b** from the opening **86** of the second blade air passage **85** and the insert opening **95o** of the second insert **95b**. However, a slight amount of the cooling air **Ac** flowing into the end cover **100** flows into the intra-blade second cavity **C2** inside the second blade air passage **85** from a gap between the seal flange **88** provided in an edge of the opening **86** of the second blade air passage **85** and the outer peripheral plate portion **96** of the second insert **95b**. The cooling air **Ac** flowing into the outer peripheral plate portion **96** is ejected to the outer peripheral side of the outer peripheral plate portion **96** from the plurality of impingement holes **97** formed in the outer peripheral plate portion **96**, and flows into the intra-blade second cavity **C2**. The cooling air **Ac** collides with a portion having a back-to-back relationship with the pressure side second blade surface portion **55s** and a portion having a back-to-back relationship with the suction side second blade surface portion **54s** on the second passage defining surface **85p**, and performs the impingement cooling on these portions.

The cooling air **Ac** flowing into the intra-blade second cavity **C2** is ejected into the combustion gas passage **49** from the plurality of pressure side second ejection holes **87ps** and the plurality of suction side second ejection holes **87ns**.

In the present modification example, as in the first embodiment, the cooling air **Ac** flowing into the first insert **90b** disposed inside the first blade air passage **81** also performs the impingement cooling on the first passage defining surface **81p**. Furthermore, a portion of the cooling air **Ac** flows into the second insert **95b** to perform the impingement cooling on the second passage defining surface **85p**. Therefore, in the present modification example, as in the first embodiment, the stator vane **50b** can be more efficiently cooled, and a usage amount of the cooling air **Ac** can be reduced, compared to when the cooling air **Ac** flowing into one insert is ejected to the combustion gas passage immediately after the cooling air **Ac** performs the impingement cooling on the inside of the blade body.

However, in the present modification example, without performing the impingement cooling on the first passage defining surface **81p**, as described above, a portion of the cooling air **Ac** flowing into the cavity **72** of the inner shroud **60i** flows into the intra-blade first cavity **C1** from the gap between the seal flange **84** provided in the edge of the first opening **82f** of the first blade air passage **81** and the outer peripheral plate portion **91** of the first insert **90b**. In addition, in the present modification example, without performing the impingement cooling on the second passage defining surface **85p**, as described above, a portion of the cooling air **Ac** flowing into the end cover **100** flows into the intra-blade second cavity **C2** from the gap between the seal flange **88** provided in the edge of the opening **86** of the second blade air passage **85** and the outer peripheral plate portion **96** of the second insert **95b**. Therefore, in the present modification example, an impingement cooling effect of the blade body **51** is lower than that in the first embodiment. In other words,

the impingement cooling effect of the blade body **51** of the first embodiment is higher than that in the present modification example.

As described above, as in the first embodiment, in the first insert **90b** and the second insert **95b**, the tube-height opening side **Dih2** may be fixed to the blade body **51**, or as in the present modification example, the tube-height sealing side **Dih1** may be fixed to the blade body **51**.

Although the present modification example is a modification example of the first embodiment, the second embodiment may be configured in the same manner as the present modification example.

[Second Modification Example of Stator Vane]

Hereinafter, a second modification example of the first embodiment of the stator vane according to the present invention will be described with reference to FIG. 10.

A stator vane **50c** of the present modification example is different from the stator vane **50** of the first embodiment in that an opening of a first blade air passage **81c**, an opening of a second blade air passage **85c**, and an end cover **100c** are disposed to be different. In addition, the stator vane **50c** of the present modification example is different from the stator vane **50** of the first embodiment in that a shape and an attachment method of a first insert **90c** and an attachment method of a second insert **95c** are different, and other configurations are the same.

Both the first blade air passage **81c** and the second blade air passage **85c** of the present modification example extend in the blade-height direction **Dh**, as in the first embodiment.

However, in the first blade air passage **81c** of the present modification example, an end on the radial inner side **Dri** which is the blade-height first side **Dh1** is open, and an end on the radial outer side **Dro** which is the blade-height second side **Dh2** is closed. The opening **82f** on the radial inner side **Dri** of the first blade air passage **81c** is open on the counter-gas path surface **65** of the inner shroud **60i**. In addition, in the second blade air passage **85c**, an end on the radial inner side **Dri** which is the blade-height first side **Dh1** is open, and an end on the radial outer side **Dro** which is the blade-height second side **Dh2** is closed. An opening **86c** of the second blade air passage **85c** is open on the counter-gas path surface **65** of the inner shroud **60i**.

As described above, in the present modification example, in both the first blade air passage **81c** and the second blade air passage **85c**, the end on the radial inner side **Dri** which is the blade-height first side **Dh1** is open.

The first insert **90c** of the present modification example includes the outer peripheral plate portion **91**, the sealing plate portion **93**, and a flange portion **94c**. The outer peripheral plate portion **91** has a tubular shape, and extends in the tube-height direction **Dih**. The sealing plate portion **93** closes an end of the outer peripheral plate portion **91** on the tube-height sealing side **Dih1**. Meanwhile, the sealing plate portion is not provided in an end portion of the outer peripheral plate portion **91** on the tube-height opening side **Dih2**. Therefore, the insert opening **90o** for introducing the cooling air **Ac** into the outer peripheral plate portion **91** is formed in the end portion of the outer peripheral plate portion **91** on the tube-height opening side **Dih2**. Unlike the flange portion **94** of the first insert **90** in the first embodiment, the flange portion **94c** is a portion of the outer peripheral surface of the outer peripheral plate portion **91**, and spreads toward the outer peripheral side from a position separated by a predetermined distance to the tube-height sealing side **Dih1** from the end of the tube-height opening side **Dih2** of the outer peripheral plate portion **91**. Therefore, the flange portion **94c** of the first insert **90c** has a shape in

21

which a portion is cut out. The predetermined distance is greater than the height of the outer peripheral plate portion 103 of the end cover 100.

The outer peripheral plate portion 91 of the first insert 90c is disposed inside the first blade air passage 81c so that the tube-height opening side Dih2 faces the blade-height first side Dh1, and a gap exists between the outer peripheral plate portion 91 and the first passage defining surface 81p. The flange portion 94c is connected to the edge of the first opening 82f of the first blade air passage 81c.

As in the second insert 95 of the first embodiment, the second insert 95c of the present modification example includes the outer peripheral plate portion 96, the sealing plate portion 98, and the flange portion 99. However, unlike the first embodiment, the outer peripheral plate portion 96 of the second insert 95c of the present modification example is disposed inside the second blade air passage 85c so that the tube-height opening side Dih2 faces the blade-height first side Dh1, and a gap exists between the outer peripheral plate portion 91 and the second passage defining surface 85p of the blade body 51 defining the second blade air passage 85c. The flange portion 99 is connected to the edge of the opening 86c of the second blade air passage 85c to close the gap between the outer peripheral plate portion 96 and the second passage defining surface 85p.

As in the end cover 100 of the first embodiment, the end cover 100c includes the top plate portion 101 and the outer peripheral plate portion 102. However, the end cover 100c of the present modification example is disposed on the blade-height first side Dh1 of the blade body 51. The top plate portion 101 of the end cover 100c faces a region where the first blade air passage 81c and the second blade air passage 85c are disposed, at an interval in the blade-height direction Dh, on the counter-gas path surface 65 of the inner shroud 60i. The outer peripheral plate portion 102 of the end cover 100c is connected to an edge of the region where the first blade air passage 81c and the second blade air passage 85c exist, on the counter-gas path surface 65 of the inner shroud 60i. The tube-height opening side Dih2 of the outer peripheral plate portion 91 of the first insert 90c protrudes to the radial inner side Dri from the top plate portion 101 of the end cover 100c.

In the present modification example, the cooling air Ac also flows into the cavity 72 of the outer shroud 60o from the radial outer side Dro of the outer shroud 60o. In addition, the cooling air Ac flows into the cavity 72 of the inner shroud 60i from the radial inner side Dri of the inner shroud 60i.

As in the first embodiment, a portion of the cooling air Ac flowing into the cavity 72 of the outer shroud 60o flows into the front side blade air passage 80f from the opening 80fo of the front side blade air passage 80f. In addition, as in the first embodiment, the other portion of the cooling air Ac flowing into the cavity 72 of the outer shroud 60o also flows into the rear side blade air passage 80b from the opening 80bo of the rear side blade air passage 80b.

The cooling air Ac flowing into the cavity 72 of the inner shroud 60i flows into the outer peripheral plate portion 91 of the first insert 90c from the insert opening 90o of the first insert 90c. The cooling air Ac flowing into the outer peripheral plate portion 91 is ejected to the outer peripheral side of the outer peripheral plate portion 91 from the plurality of impingement holes 92 formed in the outer peripheral plate portion 91, and flows into the intra-blade first cavity C1. The cooling air Ac collides with the first passage defining surface 81p, and performs the impingement cooling on the first passage defining surface 81p.

22

A portion of the cooling air Ac flowing into the intra-blade first cavity C1 is ejected into the combustion gas passage 49 from the plurality of pressure side first ejection holes 83pf and the plurality of suction side first ejection holes 83nf. The remaining portion of the cooling air Ac flowing into the intra-blade first cavity C1 flows inside the intra-blade first cavity C1 toward the radial inner side Dri which is the blade-height first side Dh1, and flows into the end cover 100c through the cutout portion of the flange portion 94c of the first insert 90c and the opening 82f of the first blade air passage 81c.

The cooling air Ac flowing into the end cover 100c flows into the outer peripheral plate portion 96 of the second insert 95c from the opening 86c of the second blade air passage 85c and the insert opening 95o of the second insert 95c. The cooling air Ac flowing into the outer peripheral plate portion 96 is ejected to the outer peripheral side of the outer peripheral plate portion 96 from the plurality of impingement holes 97 formed in the outer peripheral plate portion 96, and flows into the intra-blade second cavity C2. The cooling air Ac collides with the second passage defining surface 85p, and performs the impingement cooling on the second passage defining surface 85p.

The cooling air Ac flowing into the intra-blade second cavity C2 is ejected into the combustion gas passage 49 from the plurality of pressure side second ejection holes 87ps and the plurality of suction side second ejection holes 87ns.

In the present modification example, as in the first embodiment, the cooling air Ac flowing into the first insert 90c disposed inside the first blade air passage 81c also performs the impingement cooling on the first passage defining surface 81p. Furthermore, a portion of the cooling air Ac flows into the second insert 95c, and performs the impingement cooling on the second passage defining surface 85p. Therefore, in the present modification example, as in the first embodiment, the stator vane 50c can be more efficiently cooled, and a usage amount of the cooling air Ac can be reduced, compared to when the cooling air Ac flowing into one insert is ejected to the combustion gas passage immediately after the cooling air Ac performs the impingement cooling on the inside of the blade body.

However, in the present modification example, the cooling air Ac flowing into the first insert 90c flows to the blade-height second side Dh2 inside the first insert 90c, and is ejected from the impingement hole 92. Thereafter, the cooling air Ac flows toward the blade-height first side Dh1 inside the intra-blade first cavity C1, and flows into the second insert 95c. Therefore, in the present modification example, the cooling air Ac reciprocates in the blade-height direction Dh inside the first blade air passage 81c. Therefore, a flow path length through which the cooling air Ac flows is lengthened, and flow resistance of the cooling air Ac increases. As a result, in the present modification example, the pressure of the cooling air Ac flowing into the second insert 95c decreases. Therefore, in the present modification example, the impingement cooling effect of the blade body 51c is lower than that in the first embodiment. In other words, the impingement cooling effect of the blade body 51 of the first embodiment is higher than that in the present modification example.

As described above, out of the blade-height first side Dh1 and the blade-height second side Dh2, a side on which both the first blade air passage and the second blade air passage are open may be the blade-height second side Dh2 as in the first embodiment, or may be the blade-height first side Dh1 as in the present modification example. In addition, the tube-height opening side Dih of the second insert may face

the blade-height second side Dh2 as in the first embodiment, or may face the blade-height first side Dh1 as in the present modification example.

Although the present modification example is a modification example of the first embodiment, the second embodiment may be configured in the same manner as the present modification example.

[Third Modification Example of Stator Vane]

Hereinafter, a third modification example of the first embodiment of the stator vane according to the present invention will be described with reference to FIG. 11.

A stator vane 50d of the present modification example is a stator vane in which an impingement plate 78 is added to each of the inside of the outer shroud 60o and the inside of the inner shroud 60i in the stator vane 50 of the first embodiment.

The impingement plate 78 inside the outer shroud 60o partitions the cavity 72 of the outer shroud 60o into two spaces in the blade-height direction Dh. The impingement plate 78 has a plurality of impingement holes 79 penetrating in the blade-height direction Dh.

The impingement plate 78 inside the inner shroud 60i partitions the cavity 72 of the inner shroud 60i into two spaces in the blade-height direction Dh. The impingement plate 78 has a plurality of impingement holes 79 penetrating in the blade-height direction Dh.

The cooling air Ac flowing into the cavity 72 of the outer shroud 60o is ejected from the plurality of impingement holes 79 of the impingement plate 78, collides with the counter-gas path surface 65 of the outer shroud 60o, and performs the impingement cooling on the counter-gas path surface 65. As in the first embodiment, a portion of the cooling air Ac performing the impingement cooling on the counter-gas path surface 65 flows into the front side blade air passage 80f from the opening 80fo of the front side blade air passage 80f. In addition, as in the first embodiment, the other portion of the cooling air Ac performing the impingement cooling on the counter-gas path surface 65 flows into the rear side blade air passage 80b from the opening 80bo of the rear side blade air passage 80b.

The cooling air Ac flowing into the cavity 72 of the inner shroud 60i is ejected from the plurality of impingement holes 79 of the impingement plate 78, collides with the counter-gas path surface 65 of the inner shroud 60i, and performs the impingement cooling on the counter-gas path surface 65. As in the first embodiment, a portion of the cooling air Ac performing the impingement cooling on the counter-gas path surface 65 flows into the first insert 90. As in the first embodiment, the cooling air Ac flowing into the first insert 90 performs the impingement cooling on the first passage defining surface 81p, and thereafter, performs the impingement cooling on the second passage defining surface 85p.

As described above, in the present modification example, the cooling air Ac flowing into the cavity 72 of the inner shroud 60i can perform the impingement cooling three times on the inside of the stator vane 50d. Therefore, in the present modification example, the stator vane 50d can be more efficiently cooled, and a usage amount of the cooling air Ac can be reduced, compared to the first embodiment and each modification example thereof.

Although the present modification example is a modification example of the first embodiment, as in the present modification example, the impingement plate 78 may be added to the second embodiment, the first modification example, and the second modification example.

[Other Modification Examples of Stator Vane]

In each of the above-described embodiments and modification examples, the blade-height first side Dh1 is the radial inner side Dri, and the blade-height second side Dh2 is the radial outer side Dro. However, the blade-height first side Dh1 may be the radial outer side Dro, and the blade-height second side Dh2 may be the radial inner side Dri.

The stator vane of each of the above-described embodiments and modification examples includes two blade air passages as the intermediate blade air passages 80m, one of which is the first blade air passage, and the other of which is the second blade air passage. However, the stator vane may include three or more blade air passages as the intermediate blade air passages 80m, one of which may be used as the first blade air passage, and another one of which may be used as the second blade air passage. In addition, both the first blade air passage and the second blade air passage do not need to be passages between the front side blade air passage 80f and the rear side blade air passage 80b. For example, the first blade air passage may be one of the intermediate blade air passages 80m, and the second blade air passage may be the rear side blade air passage 80b.

All of the stator vanes of each of the above-described embodiments and modification examples are the stator vanes forming the first-stage stator vane row 46. However, the stator vane may be a stator vane forming a stator vane row closer to the axial downstream side Dad than the first-stage stator vane row 46 is.

The embodiments and modification examples of the present disclosure have been described in detail above. However, the present disclosure is not limited to the above-described embodiments and modification examples. Various additions, changes, replacements, or partial deletions can be made within the scope that does not deviate from the conceptual idea and the gist of the present disclosure derived from the contents defined in the scope of the appended claims and the equivalent thereof.

[Additional Notes]

For example, the stator vane in the above-described embodiment and modification example is understood as follows.

- According to a first aspect, there is provided the stator vane provided in the gas turbine 10. The stator vane includes the blade bodies 51, 51a, and 51c having a blade shape in a cross section and extending in the blade-height direction Dh having a direction component perpendicular to the cross section, the first inserts 90, 90a, 90b, and 90c and the second inserts 95, 95a, 95b, and 95c which have a tubular shape, extend in the tube-height direction Dih, and are disposed inside the blade bodies 51, 51a, and 51c so that the tube-height direction Dih faces the blade-height direction Dh, and the end covers 100, 100a, and 100c. The blade bodies 51, 51a, and 51c include the plurality of blade air passages 80 extending in the blade-height direction Dh inside the blade bodies 51, 51a, and 51c. In the plurality of blade air passages 80, both the first blade air passages 81, 81a, and 81c and the second blade air passages 85, 85a, and 85c have an open end on the blade-height one side which is one side of the blade-height first side Dh1 and the blade-height second side Dh2 in the blade-height direction Dh. Both the first inserts 90, 90a, 90b, and 90c and the second inserts 95, 95a, 95b, and 95c include the outer peripheral plate portions 91 and 96 having a tubular shape and extending in the tube-height direction Dih, and the sealing plate portions 93 and 98 that close the ends on the tube-height sealing side Dih1 which is one side of the

outer peripheral plate portions 91 and 96 in the tube-height direction Dih out of two sides in the tube-height direction Dih. The outer peripheral plate portions 91 and 96 have the plurality of impingement holes 92 and 97 penetrating from the inside to the outside of the tubular outer peripheral plate portions 91 and 96. The tube-height opening side Dih2 which is the other side of the outer peripheral plate portions 91 and 96 in the tube-height direction Dih is open. The outer peripheral plate portion 91 of the first inserts 90, 90a, 90b, and 90c has a gap existing between the outer peripheral plate portion 91 of the first insert 90 and the first passage defining surface 81p of the blade bodies 51, 51a, and 51c defining the first blade air passage 81, and is disposed inside the first blade air passage 81, 81a, and 81c so that cooling air Ac flows into the outer peripheral plate portion 91 from the opening of the first inserts 90, 90a, 90b, and 90c. The outer peripheral plate portion 96 of the second inserts 95, 95a, 95b, and 95c is configured so that the tube-height opening side Dih2 of the second inserts 95, 95a, 95b, and 95c faces the blade-height one side, has a gap existing between the outer peripheral plate portion 96 of the second inserts 95, 95a, 95b, and 95c and the second passage defining surface 85p of the blade bodies 51, 51a, and 51c defining the second blade air passage 85, and is disposed inside the second blade air passages 85, 85a, and 85c so that the cooling air Ac flows from the opening of the second inserts 95, 95a, 95b, and 95c. The end covers 100, 100a, and 100c are provided on the blade-height one side of the blade body 51 so that the cooling air Ac ejected from the plurality of impingement holes 92 of the first inserts 90, 90a, 90b, and 90c to between the outer peripheral plate portion 91 of the first inserts 90, 90a, 90b, and 90c and the first passage defining surface 81p is guided into the second inserts 95, 95a, 95b, and 95c from the opening of the second inserts 95, 95a, 95b, and 95c through the opening of the first blade air passage 81, and cover the opening of the first blade air passage 81 and the opening of the second inserts 95, 95a, 95b, and 95c.

In the present aspect, the cooling air Ac flowing into the first inserts 90, 90a, 90b, and 90c disposed inside the first blade air passages 81, 81a, and 81c performs the impingement cooling on the first passage defining surface 81p. Furthermore, at least a portion of the cooling air Ac flows into the second inserts 95, 95a, 95b, and 95c disposed inside the second blade air passages 85, 85a, and 85c. The cooling air Ac flowing into the second inserts 95, 95a, 95b, and 95c performs the impingement cooling on the second passage defining surface 85p. Therefore, in the present aspect, the stator vane can be more efficiently cooled, and a usage amount of the cooling air Ac can be reduced, compared to when the cooling air Ac flowing into one insert is ejected to the combustion gas passage immediately after the cooling air Ac performs the impingement cooling on the inside of the blade body.

(2) According to a second aspect of the stator vane, in the stator vane according to the first aspect, the blade surfaces which are the outer surfaces of the blade bodies 51, 51a, and 51c include the first blade surface portions 54f and 55f having a back-to-back positional relationship with the first passage defining surface 81p, and the second blade surface portions 54s and 55s having a back-to-back positional relationship with the second passage defining surface 85p. The plurality of impingement holes 92 are formed in portions facing the

first blade surface portions 54f and 55f in the outer peripheral plate portion 91 in the first inserts 90, 90a, 90b, and 90c. The plurality of impingement holes 97 are formed in portions facing the second blade surface portions 54s and 55s in the outer peripheral plate portion 96 of the second inserts 95, 95a, 95b, and 95c. In the present aspect, the blade surface exposed to the combustion gas can be effectively cooled.

(3) According to a third aspect of the stator vane, in the stator vane according to the second aspect, the blade bodies 51, 51a and 51c have the plurality of ejection holes 87ns and 87ps penetrating from the second passage defining surface 85p to the second blade surface portions 54s and 55s. The positions of the second blade surface portions 54s and 55s on the blade surface are positions where the pressure of the portion along the second blade surface portions 54s and 55s outside the blade bodies 51, 51a, and 51c while the gas turbine 10 is driven is lower than the pressure of the portion along the first blade surface portions 54f and 55f outside the blade bodies 51, 51a, and 51c.

(4) According to a fourth aspect of the stator vane, in the stator vane according to the third aspect, the blade bodies 51 and 51c include the leading edge 52 extending in the blade-height direction Dh, the trailing edge 53 extending in the blade-height direction Dh, and the pressure surface 55 and the suction surface 54 which extend in the blade-height direction Dh and connect the leading edge 52 and the trailing edge 53. The first blade surface portions 54f and 55f are portions of one blade surface of the pressure surface 55 and the suction surface 54. The second blade surface portions 54s and 55s are located closer to a side of the trailing edge 53 than the first blade surface portions 54f and 55f are in the one blade surface.

(5) According to a fifth aspect of the stator vane, in the stator vane according to the third aspect, the blade body 51a includes the leading edge 52 extending in the blade-height direction Dh, the trailing edge 53 extending in the blade-height direction Dh, and the pressure surface 55 and the suction surface 54 which extend in the blade-height direction Dh and connect the leading edge 52 and the trailing edge 53. The first blade surface portion 55f is a portion of the pressure surface 55. The second blade surface portion 54s is a portion of the suction surface 54.

(6) According to a sixth aspect of the stator vane, in the stator vane according to any one aspect of the first aspect to the fifth aspect, in the first blade air passages 81 and 81a, an end on the blade-height first side Dh1 and an end on the blade-height second side Dh2 of the first blade air passages 81 and 81a are open. In the second blade air passages 85 and 85a, an end on the blade-height first side Dh1 of the second blade air passages 85 and 85a is closed, and an end on the blade-height second side Dh2 is open. The first inserts 90 and 90a include the flange portion 94 spreading from an end on the tube-height opening side Dih2 in the outer peripheral plate portion 91 of the first inserts 90 and 90a toward the outer peripheral side of the outer peripheral plate portion 91 of the first inserts 90 and 90a, extending to the first passage defining surface 81p, and connected to the blade body 51.

The second inserts 95 and 95a include the flange portion 99 spreading from an end on the tube-height opening side Dih2 in the outer peripheral plate portion 96 of the second inserts 95 and 95a toward the outer peripheral side of the

outer peripheral plate portion 96 of the second inserts 95 and 95a, extending to the second passage defining surface 85p, and connected to the blade body 51. The outer peripheral plate portion 91 of the first inserts 90 and 90a is disposed inside the first blade air passages 81 and 81a so that the tube-height opening side Dih2 of the first inserts 90 and 90a faces the blade-height first side Dh1. The outer peripheral plate portion 96 of the second inserts 95 and 95a is disposed inside the second blade air passages 85 and 85a so that the tube-height opening side Dih2 of the second inserts 95 and 95a faces the blade-height second side Dh2.

In the present aspect, a structure of each insert is not complicated, and the impingement cooling effect of the blade body 51 can be improved.

(7) According to a seventh aspect of the stator vane, the stator vane according to any one aspect of the first aspect to the sixth aspect further includes the first guide member 110 that allows the displacement of the first inserts 90, 90a, 90b, and 90c in the tube-height direction Dih and that regulates the displacement of the first inserts 90, 90a, 90b, and 90c in a spreading direction of the cross section of the first inserts 90, 90a, 90b, and 90c, inside the first blade air passages 81, 81a, and 81c, and the second guide member 115 that allows the displacement of the second inserts 95, 95a, 95b, and 95c in the tube-height direction Dih and that regulates the displacement of the second inserts 95, 95a, 95b, and 95c in a spreading direction of the cross section of the second inserts 95, 95a, 95b, and 95c, inside the second blade air passages 85, 85a, and 85c.

In the present aspect, even when the gas turbine 10 is driven so that there is a difference in thermal deformation amounts between the outer peripheral plate portions 91 of the first inserts 90, 90a, 90b, and 90c and the first passage defining surface 81p due to a temperature difference theretwix, a distance between the outer peripheral plate portions 91 of the first inserts 90, 90a, 90b, and 90c and the first passage defining surface 81p can be kept substantially constant, and a desired impingement cooling effect can be obtained. In addition, in the present aspect, even when the gas turbine 10 is driven so that there is a difference in thermal deformation amounts between the outer peripheral plate portions 96 of the second inserts 95, 95a, 95b, and 95c and the second passage defining surface 85p due to a temperature difference theretwix, a distance between the outer peripheral plate portions 96 of the second inserts 95, 95a, 95b, and 95c and the second passage defining surface 85p can be kept substantially constant, and a desired impingement cooling effect can be obtained.

(8) According to an eighth aspect of the stator vane, in the stator vane according to the seventh aspect, the first guide member 110 includes the first groove member 111 having the first groove 112 extending in the tube-height direction Dih, and the first convex member 113 entering the inside of the first groove 112 and being relatively movable in the tube-height direction Dih with respect to the first groove 112. One member of the first groove member 111 and the first convex member 113 is fixed to the first inserts 90 and 90a, and the other member is fixed to the first passage defining surface 81p. The second guide member 115 includes the second groove member 116 having the second groove 117 extending in the tube-height direction Dih, and the second convex member 118 entering the second groove 117 and being relatively movable in the tube-height direction Dih with respect to the second groove 117. One member of the second groove member 116 and the

second convex member 118 is fixed to the second inserts 95 and 95a, and the other member is fixed to the second passage defining surface 85p.

(9) According to a ninth aspect of the stator vane, the stator vane according to the sixth aspect further includes the first guide member 110 that allows the displacement of the first inserts 90 and 90a in the tube-height direction Dih and that regulates the displacement of the first inserts 90 and 90a in a spreading direction of the cross section of the first inserts 90 and 90a, inside the first blade air passages 81 and 81a, and the second guide member 115 that allows the displacement of the second inserts 95 and 95a in the tube-height direction Dih and that regulates the displacement of the second inserts 95 and 95a in a spreading direction of the cross section of the second inserts 95 and 95a, inside the second blade air passages 85 and 85a. The first guide member 110 includes the first groove member 111 having the first groove 112 extending in the tube-height direction Dih, and the first convex member 113 entering the inside of the first groove 112 and being relatively movable in the tube-height direction Dih with respect to the first groove 112. One member of the first groove member 111 and the first convex member 113 is fixed to the outer peripheral plate portion 91 of the first inserts 90 and 90a, and the other member is fixed to the first passage defining surface 81p of the blade bodies 51 and 51a. The second guide member 115 includes the second groove member 116 having the second groove 117 extending in the tube-height direction Dih, and the second convex member 118 entering the second groove 117 and being relatively movable in the tube-height direction Dih with respect to the second groove 117. One member of the second groove member 116 and the second convex member 118 is fixed to the sealing plate portion 98 of the second inserts 95 and 95a, and the other member is fixed to a portion closed in an end on the blade-height first side Dh1 in the second blade air passages 85 and 85a in the blade bodies 51 and 51a.

(10) According to a tenth aspect of the stator vane, the stator vane according to any one aspect from the first aspect to the ninth aspect further includes the first shroud 60i provided in an end on the blade-height first side Dh1 in the blade bodies 51, 51a, and 51c, the second shroud 60o provided in an end on the blade-height second side Dh2 in the blade bodies 51, 51a, and 51c, and the impingement plate 78 having the plurality of impingement holes 79. The first shroud 60i includes the shroud body 61 having the gas path surface 64 facing the blade-height second side Dh2, and the counter-gas path surface 65 facing a side opposite to the gas path surface 64, and the peripheral wall 71 provided along the peripheral edge of the shroud body 61 and protruding from the counter-gas path surface 65 to the blade-height first side Dh1. The impingement plate 78 is formed of the shroud body 61 and the peripheral wall 71, and is fixed to the first shroud 60i so that the cavity 72 inside the concave portion recessed toward the blade-height second side Dh2 is partitioned into a space on the blade-height first side Dh1 and a space on the blade-height second side Dh2, and the plurality of impingement holes 79 of the impingement plate 78 extend in the blade-height direction Dh.

In the present aspect, the cooling air Ac flowing into the stator vane can perform the impingement cooling three times on the inside of the stator vane. Therefore, in the present

aspect, the stator vane can be efficiently cooled, and a usage amount of the cooling air Ac can be reduced.

For example, the gas turbine in the above-described embodiment is understood as follows.

(11) According to an eleventh aspect, there is provided the gas turbine including the stator vane according to any one aspect of the first aspect to the tenth aspect, the rotor **41** that rotates around the axis Ar, and the casing **45** that covers the outer peripheral side of the rotor **41**. The stator vane is fixed to the inner peripheral surface of the casing **45**. 5 10

INDUSTRIAL APPLICABILITY

According to an aspect of the present disclosure, a stator 15 vane can be effectively cooled, and a usage amount of cooling air can be minimized while durability is improved.

The invention claimed is:

1. A stator vane provided in a gas turbine, comprising:
 a blade body having a blade shape in a cross-section and
 extending in a blade-height direction having a direction
 component perpendicular to the cross section;
 a first insert and a second insert which have a tubular
 shape, extend in a tube-height direction, and are dis- 10
 posed inside the blade body so that the tube-height
 direction faces the blade-height direction; and
 an end cover,
 wherein the blade body includes a plurality of blade air
 passages extending in the blade-height direction inside 20
 the blade body,
 in the plurality of blade air passages, both a first blade air
 passage and a second blade air passage have an open
 end on a blade-height one side which is one side of a
 blade-height first side and a blade-height second side in 25
 the blade-height direction,
 both the first insert and the second insert include
 an outer peripheral plate portion having a tubular shape
 and extending in the tube-height direction, and
 a sealing plate portion that closes an end on a tube- 30
 height sealing side which is one side of the outer
 peripheral plate portion in the tube-height direction
 out of two sides in the tube-height direction,
 the outer peripheral plate portion has a plurality of
 impingement holes penetrating from an inside to an 35
 outside of the tubular outer peripheral plate portion,
 a tube-height opening side which is the other side of the
 outer peripheral plate portion in the tube-height direc-
 tion is open,
 the outer peripheral plate portion of the first insert has a 40
 gap existing between the outer peripheral plate portion
 of the first insert and a first passage defining surface of
 the blade body defining the first blade air passage, and
 is disposed inside the first blade air passage so that
 cooling air flows into the outer peripheral plate portion 45
 from an opening of the first insert,
 the outer peripheral plate portion of the second insert is
 configured so that the tube-height opening side of the
 second insert faces the blade-height one side, has a gap
 existing between the outer peripheral plate portion of 50
 the second insert and a second passage defining surface
 of the blade body defining the second blade air passage,
 and is disposed inside the second blade air passage so
 that the cooling air flows from an opening of the second
 insert,
 the end cover is provided on the blade-height one side of 55
 the blade body so that the cooling air ejected from the
 plurality of impingement holes of the first insert to
 between the outer peripheral plate portion of the first
 insert and the first passage defining surface is guided
 into the second insert from the opening of the second 60
 insert through the opening of the first blade air passage,
 and covers the opening of the first blade air passage and
 the opening of the second insert,
 in the first blade air passage, an end on the blade-height 65
 first side and an end on the blade-height second side of
 the first blade air passage are open,

32

in the second blade air passage, an end on the blade-height
 first side of the second blade air passage is closed, and
 an end on the blade-height second side is open,
 the first insert includes a flange portion spreading from an
 end on the tube-height opening side in the outer periph- 5
 eral plate portion of the first insert toward an outer
 peripheral side of the outer peripheral plate portion of
 the first insert, extending to the first passage defining
 surface, and connected to the blade body,
 the second insert includes a flange portion spreading from
 an end on the tube-height opening side in the outer periph- 10
 eral plate portion of the second insert toward an outer
 peripheral side of the outer peripheral plate portion of
 the second insert, extending to the second passage defining
 surface, and connected to the blade body,
 the outer peripheral plate portion of the first insert is
 disposed inside the first blade air passage so that the
 tube-height opening side of the first insert faces the 15
 blade-height first side, and
 the outer peripheral plate portion of the second insert is
 disposed inside the second blade air passage so that the
 tube-height opening side of the second insert faces the
 blade-height second side.
 2. The stator vane according to claim 1,
 wherein a blade surface which is an outer surface of the
 blade body includes
 a first blade surface portion having a back-to-back
 positional relationship with the first passage defining 20
 surface, and
 a second blade surface portion having a back-to-back
 positional relationship with the second passage
 defining surface,
 the plurality of impingement holes are formed in a portion
 facing the first blade surface portion in the outer
 peripheral plate portion in the first insert, and
 the plurality of impingement holes are formed in a portion
 facing the second blade surface portion in the outer 25
 peripheral plate portion in the second insert.
 3. The stator vane according to claim 2,
 wherein the blade body has a plurality of ejection holes
 penetrating from the second passage defining surface to
 the second blade surface portion, and
 a position of the second blade surface portion on the blade 30
 surface is a position where a pressure of a portion along
 the second blade surface portion outside the blade body
 is lower than a pressure of a portion along the first blade
 surface portion outside the blade body while the gas
 turbine is driven.
 4. The stator vane according to claim 3,
 wherein the blade body includes
 a leading edge extending in the blade-height direction,
 a trailing edge extending in the blade-height direction,
 and
 a pressure surface and a suction surface which extend 35
 in the blade-height direction and connect the leading
 edge and the trailing edge,
 the first blade surface portion is a portion of one blade
 surface of the pressure surface and the suction surface,
 and
 the second blade surface portion is located closer to a side 40
 of the trailing edge than the first blade surface portion
 is in the one blade surface.
 5. The stator vane according to claim 3,
 wherein the blade body includes
 a leading edge extending in the blade-height direction,

33

a trailing edge extending in the blade-height direction, and
a pressure surface and a suction surface which extend in the blade-height direction and connect the leading edge and the trailing edge,
the first blade surface portion is a portion of the pressure surface, and
the second blade surface portion is a portion of the suction surface.

6. The stator vane according to claim 1, further comprising:

a first guide member that allows displacement of the first insert in the tube-height direction and that regulates displacement of the first insert in a spreading direction of the cross section of the first insert, inside the first 15 blade air passage; and

a second guide member that allows displacement of the second insert in the tube-height direction and that regulates displacement of the second insert in a spreading direction of the cross section of the second insert, inside the second 20 blade air passage.

7. The stator vane according to claim 6, wherein the first guide member includes

a first groove member having a first groove extending in the tube-height direction, and

a first convex member entering an inside of the first groove and being relatively movable in the tube-height direction with respect to the first groove,

one member of the first groove member and the first convex member is fixed to the first insert, and the other member is fixed to the first passage defining surface, 30 the second guide member includes

a second groove member having a second groove extending in the tube-height direction, and

a second convex member entering an inside of the second groove and being relatively movable in the tube-height direction with respect to the second groove, and

one member of the second groove member and the second convex member is fixed to the second insert, and the other member is fixed to the second passage defining surface. 40

8. The stator vane according to claim 1, further comprising:

a first guide member that allows displacement of the first 45 insert in the tube-height direction and that regulates displacement of the first insert in a spreading direction of the cross section of the first insert, inside the first blade air passage; and

a second guide member that allows displacement of the second insert in the tube-height direction and that regulates displacement of the second insert in a spreading direction of the cross section of the second insert, inside the second 50 blade air passage,

wherein the first guide member includes

34

a first groove member having a first groove extending in the tube-height direction, and

a first convex member entering an inside of the first groove and being relatively movable in the tube-height direction with respect to the first groove,

one member of the first groove member and the first convex member is fixed to the outer peripheral plate portion of the first insert, and the other member is fixed to the first passage defining surface of the blade body, the second guide member includes

a second groove member having a second groove extending in the tube-height direction, and

a second convex member entering an inside of the second groove and being relatively movable in the tube-height direction with respect to the second groove, and

one member of the second groove member and the second convex member is fixed to the sealing plate portion of the second insert, and the other member is fixed to a portion closed in an end on the blade-height first side in the second blade air passage in the blade body.

9. The stator vane according to claim 1, further comprising:

a first shroud provided in an end on the blade-height first side in the blade body;

a second shroud provided in an end on the blade-height second side in the blade body; and

an impingement plate having a plurality of impingement holes,

wherein the first shroud includes

a shroud body having a gas path surface facing the blade-height second side, and a counter-gas path surface facing a side opposite to the gas path surface, and

a peripheral wall provided along a peripheral edge of the shroud body and protruding from the counter-gas path surface to the blade-height first side, and

the impingement plate is formed of the shroud body and the peripheral wall, and is fixed to the first shroud so that a cavity inside a concave portion recessed toward the blade-height second side is partitioned into a space on the blade-height first side and a space on the blade-height second side, and the plurality of impingement holes of the impingement plate extend in the blade-height direction.

10. A gas turbine comprising:

the stator vane according to claim 1;

a rotor that rotates around an axis; and

a casing that covers an outer peripheral side of the rotor, wherein the stator vane is fixed to an inner peripheral surface of the casing.
